Inventor
I. Newman
BY HIS

R. F. Bourne
ATTORNEY

UNITED STATES PATENT OFFICE.

ISIDOR NEWMAN, OF NEW YORK, N. Y.

CLOSURE FOR RECEPTACLES.

Application filed February 10, 1920. Serial No. 357,755.

To all whom it may concern:

Be it known that ISIDOR NEWMAN, a citizen of the United States, and resident of New York city, borough of Manhattan, in 5 the county of New York and State of New York, have invented certain new and useful Improvements in Closures for Receptacles, of which the following is a specification.

The object of my invention is to provide 10 an improved closure for receptacles, such as tin cans, which may be cheaply made, readily and cheaply attached to cans, and which will provide a pouring outlet for use.

My invention comprises a closure having 15 a centrally disposed threaded neck provided with an open inner end and a closed outer end, a laterally disposed web projecting from the inner end of the neck, and a flange raised from the plane of said web for attachment to the neck of a container.

Reference is had to the accompanying drawings forming part hereof, wherein,

Figure 1 is a perspective view of my improved closure;

Fig. 2 is a partly sectional view of a portion of a receptacle and the closure thereover;

Fig. 3 is a similar view showing the closure on the receptacle in position to be attached thereto;

Fig. 4 is an enlarged section illustrating the closure fastened to the neck of a receptacle, the section being taken on the line 4-4 in Fig. 5;

Fig. 5 is a plan view of Fig. 4; and

Figs. 6 and 7 are sectional details of a modification.

Similar numerals of reference indicate corresponding parts in the several views.

At 1 is indicated the neck portion of my improved closure which is tubular in form having its inner end 1^a open and its outer end closed by transverse web 1^b, the exterior of the neck being threaded at 2 to receive a

correspondingly threaded cap 3. From the inner open end of neck 1 a web 4 extends laterally and at the outer marginal portion of said web the metal is raised in a wall at 5 around the neck, which wall is provided

with a marginal flange 6. In Figs. 1, 2 and 3 said flange is curved or bent downwardly in the direction of the plane of web 4, in position to be rolled or seamed to the neck of the receptacle, whereas in the modification

in Fig. 6 the flange 6 extends laterally sub-

stantially parallel to the plane of said web. My improved closure may be made by drawing the neck 1 from a disk of suitable metal and rolling the thread 2 on the neck and then with suitable dies the raised wall 5 and 60 flange 6 may be made by striking up the metal in suitable dies.

My improved closure is adapted to fit within an opening having an out-turned neck 7 on the top 8 of a receptacle 9, such as a tin can, whereby the web 4, the inner portion of neck 1 and the out-turned wall 5 of the closure will fit within said neck and the flange 6 will rest thereon as shown in

Figs. 3 and 6. After the parts are assembled in the last named position the flange 6 may be secured to neck 7 by a suitable seam- 70

ing tool having a roller 10 rotated within the space between neck 1 and wall 5 operating with outward pressure; and a roller 11 75 bearing upon and rotating on the flange 6 will roll down said flange outside of can neck 7, when said rollers are rotated around the closure, in a well known manner of operating such tools. The closure seamed to

the neck of the can is illustrated in Figs. 4 and 7 whereby a hermetically tight seam may be effected. The top 8 of the receptacle is recessed at 8^a around neck 7, within which

recess the neck 7 extends outwardly, whereby when the closure is attached to the can top the neck 1 is partly sunken below the

level of top 8 and projects but a short distance therebeyond. The recess between the neck 1 and the out-turned wall 5 of the closure affords a space to receive the cap 3.

When the contents of the container are to be poured therefrom the cap 3 is removed and a hole is punctured in the top web 1^b of the neck 1. The cap may be screwed 95 back upon neck 1 to cover and protect the same when not in use.

By means of my improvements a closure having a pouring neck may be simply and cheaply made for attachment to the neck 100 of a container in a cheap and expeditious manner by means of rollers without requiring the use of solder to secure the closure to neck 7 and without danger of the closure becoming loosened and permitting leakage 105 at the seam.

Having thus described my invention, what I claim and desire to secure by Letters Patent is:—

1. A closure for a container comprising 110

- an imperforate threaded neck provided with a puncturable outer end, said neck having a laterally disposed web and an outwardly disposed wall spaced from and surrounding the neck, said wall having an outwardly disposed pliable flange, said wall and flange being adapted to receive the out-turned neck of a container therebetween, and a threaded cap to detachably fit said threaded neck.
2. A closure for a container comprising an imperforate neck having an open inner end and a closed puncturable outer end, a laterally disposed web extending from the open end of the neck and a bendable flange at the margin of the web raised from the plane of the web and surrounding the neck, the outer closed end of the neck extending beyond the lateral web.
- 20 3. A closure for a container comprising an imperforate neck having an open inner end and a closed puncturable outer end, a laterally disposed web extending from the open end of the neck, a wall raised from the web extending around the neck, and a bendable flange projecting outwardly from said wall.
4. A closure for a container comprising a threaded imperforate neck having an open inner end and a closed puncturable outer end, a laterally disposed web extending from said open end of the neck, a wall raised from said web surrounding and spaced from the neck, and a bendable flange extending outwardly from said wall.
- 30 5. The combination of a container having a top provided with an opening and an outwardly extending neck, a closure in said neck comprising a centrally disposed neck having a laterally extending web provided with an outwardly extending wall surrounding the last named neck, said wall having a flange, said wall and flange receiving the container top neck therebetween in frictional air-tight engagement.
- 35 Signed at New York in the county of New York and State of New York this 9th day of February A. D. 1920.
- 40 45 ISIDOR NEWMAN.
